UNITED STATES PATENT OFFICE.

ROBERT C. WALSH, OF ST. LOUIS, MISSOURI.

MERCHANDISE CABINET.

Application filed July 13, 1925, Serial No. 43,104, and in Canada September 22, 1924.

This invention relates to improvements in store fixtures, and more particularly to that type of cabinets ordinarily placed behind store counters for the storage and display 5 of small merchandise, but may also relate to the construction of counters, show cases and the like, and is an improvement on that disclosed in my former application, Serial No. 633,149, filed April 19th, 1923.

10 In my former application there is disclosed a structure embodying storage or display spaces with sliding or folding doors, drawers and the like, each provided with a locking means controlled from a cash drawer 15 or till in such a way that by suitable manipulation of the cash drawer or till all the closure members or receptacles of the device may be simultaneously locked but are, in their ordinary use, unlocked regardless 20 of whether the cash drawer is open or closed. The present invention relates more particularly to improvements in construction of the cabinet or fixtures themselves, aiming toward ease of manipulation in the 25 moving, storage or assembly of the fixtures, and relates also to improvements in the mechanism for locking the various closure members or containers of the structure with a view to providing mechanism of simplified construction and capable of operation with a small expenditure of power.

Generally speaking, the invention embodies a cabinet or the like comprising separable bottom, top, end and back sections 35 constructed to have a certain interlocking relation, whereby they may be assembled into operative form without the use of tools or fastening means, such as nails or screws. These flat sections which are easily handled 40 and stored may be taken apart with the same facility with which they may be assembled. The cabinet may be constructed in a number of separate sections adapted to be placed end to end, or may be a large 45 cabinet divided by removable vertical partitions into as many sections as desired. The locking means for each section is mounted as far as possible upon one of the members of the section, usually the back, with the 50 result that the cabinet may be taken apart with the minimum of disorganization of the locking means. The locking means is in itself a substantially balanced system of levers and connecting links which may be operated 55 with a very small expenditure of power.

In the accompanying drawings showing

one embodiment of the invention, but to which embodiment the invention is not confined, as numerous modifications of construction and arrangement may be made within 60 the scope of the invention:—

Fig. 1 is a front elevation of a pair of adjoining cabinet sections constructed according to this invention, one of said sections being open and the other partly broken 65 away to show the construction thereof and the arrangement of the locking device.

Fig. 2 is a vertical sectional view on the line 2—2, Figure 1.

Fig. 3 is a side elevation of the cash 70 drawer or till.

Referring more particularly to the drawings, A and B designate two units or sections of a cabinet constructed according to this invention, each unit of which comprises 75 essentially a bottom 11, a top 12, ends 13, and a back 14. The units may be divided by one or more vertical partitions 15 into as many sections as desired and may also be divided horizontally as desired by partitions 16 and shelves 17. The upper and lower parts of the cabinets are provided with doors or other closure means 18, preferably of the sliding type shown, but hinged closure means may be employed. 85 The space between the partitions 16 may be provided with drawers 19 or other suitable receptacles, and in one of the units, for example in the section A, a location 20 is provided for a cash drawer or till 21 shown in 90 Figure 3. It will be understood that the cabinet may consist of as many units as desired and that these may be constructed and divided as desired, or as necessary according to the nature of the merchandise 95 kept therein.

Each unit of the cabinet is a self-contained, knockdown structure which may be readily dismembered into a number of flat sections easily handled, packed, stored or 100 transported, and which sections may be easily and quickly assembled, preferably without the use of tools or fastenings, such as nails or screws, into a complete cabinet section.

The bottom 11 of each section comprises a base 22 to which stringers 23 are attached extending from front to back near the ends, and if desired in pairs at intermediate points, as at 24. The stringer pairs 24 are 110 located wherever it is desired to have a vertical partition 15 and the stringers of these

pairs are separated a distance substantially equal to the thickness of the partition. The front and back ends of all stringers in a unit are connected by frames 25 and 26 respectively, which are preferably also connected to the base 21, thus forming a permanent rigid box-like structure. Floors 27 are provided extending from one stringer to the next. Where stringer pairs 24 are provided, 10 the floors do not span the spaces between the stringers but leave these open for the insertion of the vertical partitions 15. When a unit is to be the end unit of a row or 15 battery of cabinets, it is provided at the outer end with a skirt board 28 spaced from the end stringer 23 a distance substantially equal to the thickness of the end 13. Where 20 two units are erected end to end, the adjacent end stringers thereof will be spaced apart to receive between them the end members 13. The end member 13 and vertical divisions 15 (if any) drop into the spaces between the 25 stringers or stringers and skirt board 28, so that they are held at their lower ends in properly spaced relation. These ends and 30 divisions are flat members of appropriate shape, usually panelled frames, and are preferably in a single piece extending from top to bottom and front to back of the cabinet. The top comprises a board or the like, 35 designated 29, having recesses or channels 30 therein to receive the upper ends of the end members and vertical divisions, the said channels being formed either by grooving the top or by attaching battens or the like thereto. The top is also provided near the back edge with a channel 31 to receive the upper end of the back 14 and, when sliding doors are used, the top is further provided 40 near the front edge with a groove 32 to receive sliding doors. The back of each cabinet unit is formed of as many boards or panelled frames as necessary, each preferably extending from the bottom to the top. 45 At the lower end each back section rests upon the back frame 26 and at the upper end each section is received in the channel 31 of the top. Where vertical divisions 15 are used, it is preferable to locate the joints 50 33 between adjacent back members immediately in rear of such division, as shown in Figure 1.

The groove 32 is deeper than is necessary merely to accommodate the top edges of the doors sliding in it, so that when the doors are in place there will exist an empty portion of the groove above the top edges of the doors. Toward the sides of each cabinet unit, the upper part of the groove 32 is 55 filled by blocks 34, preferably tapered or bevelled at their adjacent ends. These blocks hold the doors when in closed position, against being lifted out of or off their bottom guides 35 and thus removed. When, 60 however, the doors are unlocked and partly 65

open, they register with the full depth central portion of the groove 32 and may be lifted sufficiently to disengage them from their bottom guides. When thus lifted, the lower ends of the doors may be drawn forwardly and the doors lowered out of the top groove and thus separated from the cabinet for cleaning, reglazing or the like. The length of the full depth portion of the groove must obviously be slightly greater 70 than the width of a single door. This construction is not confined to the upper sliding doors but is used for all sliding doors 75 of the cabinet.

When the parts of each unit have been 80 assembled in the relation described, they are secured together by suitable fastening means, designated 36, such as hooks or bolts. These fastening means are preferably arranged to connect the top, bottom and ends together 85 and also to connect the back to the ends at the bottom and at intermediate points if desired. The sliding doors may now be put in place by thrusting them up into the full depth central portions of the top grooves 32 and swinging the lower ends into register 90 with the bottom guides and finally lowering the doors into the bottom guides. As already stated, many variations may be made 95 in the details of construction without departing from the broad principle just described.

As stated in my former application already identified, common locking means is 100 provided for the several closure members of each cabinet section, said locking means being arranged to be operated by predetermined movement of the cash drawer. Briefly described, this locking means embodies a 105 series of upper and lower rocking levers 37 and 38 respectively, pivoted to the back members of the cabinet and connected by links 39. Levers or other means, designated as a whole by the numeral 40, are provided 110 in operative connection with the levers 37 or 38 and links 39 for locking engagement with the various closure members of the cabinet. For more complete understanding 115 of the construction, arrangement and operation of this mechanism, reference may be had to my prior application aforementioned. In that application, provision was made for the establishment of operative connection between the locking means of adjoining cabinet units, so that the locking means of a 120 number of units might be controlled from a single cash drawer. This means comprised a shaft in each unit and a gear connected to one of the links of the locking mechanism. The shafts of adjoining units were disposed 125 in alignment and coupled together.

According to the present invention, the 130 method of coupling the locking means of adjoining cabinet units together is greatly improved, simplified and cheapened by the

elimination of the shafts and gear connections to the links 39 and the substitution of a simple rocking lever 43 extending from one unit to the next, or from section to section of 5 a unit, as shown, the arms of this lever being connected by links 44 to the rocking levers of the adjacent units or sections of units. This arrangement is much easier and cheaper to manufacture and install and requires much less power for its operation. Also, the units may be very easily separated for movement from one location to another, merely by withdrawing the pivot pins connecting the links 44 to the levers 37. A further advantage resulting from this method of connecting the sections is that the upper levers may be placed much lower down in the cabinet, as shown, and the links 39 thereby shortened. The sliding locking bolts of the 20 upper doors with their gear connection to the shafts may be eliminated and replaced by the simple rocking levers 45 connected by light links 46 with the levers 37 for movement into and out of locking position with 25 respect to the door catches.

The locking actuating mechanism formerly located on the bottom of the cash drawer is now transferred to the side and includes a lever 47 pivoted intermediate its ends to a 30 section end or partition at one side of the space 20. The rear or inner end of this lever is connected in any suitable way to the locking mechanism, for example, to one of the links 39 by means of a link 48. The front 35 end of the lever carries a roller 49 to engage in a cam groove 50 on the side of the cash drawer. As in my previous application, the cash drawer carries a manually releasable pivoted latch 51 engageable with either of 40 two catches 52 and 53 located in the cabinet one behind the other. In ordinary use, the cash drawer is pushed in until the latch slips past the front catch 52. During such movement, the roller 49 travels in the straight 45 part of the drawer groove 50. If, however, the cash drawer is pushed farther in, until the latch passes the back catch 53, the inclined or cam portion of the drawer groove is forced under the roller 49 to raise the same 50 and incline the lever 47. Movement of the lever is communicated to the locking mechanism to operate the same.

The use or operation of the cabinets is susceptible of many variations and it will therefore be understood that neither the foregoing nor the following descriptions of operation are to be regarded as in any way limitative. The number of cabinet units necessary to constitute a department or designed 55 to be under the charge of a clerk are set up and the locking devices thereof connected together so as to be operated from a single cash drawer in one of the units. The person having charge of the cabinet may therefore be 60 held responsible for the contents thereof and

will at the same time be protected by reason of the ability to lock all parts of the cabinet, providing the doors, etc. are closed, by simply moving the cash drawer to its rearmost position and locking the same. The movement of the cash drawer to such position operates in the manner already described to move the lever 47 and thereby actuate the locking mechanism of the section including the lever 37. The movement of the lever 37 70 is communicated through the links 44 and the lever 43 to the lever 37 of an adjoining section and through the levers 37 of this section to the next unit in line and so on, so that the locking devices 40 and 45 of all cabinet units in the train will be operated simultaneously to engage or disengage catches on the various closure members of the cabinet, as more fully described in my former application already identified. If it is desired 75 to disconnect the locking means of any unit of the series, this may be readily effected by withdrawing the pivot pins connecting the lever or levers 37 of that unit to the links 39 and 46; but it will be noted that such 80 manipulation of the device will not interfere with the transmission of operating force through this unit to other units. The doors when locked cannot be removed by lifting them off their bottom guides by reason of 85 the holding effect of the top, which is connected through the ends to the bottom and at the same time they are held by the locking means against movement to a position permitting removal. The locking means of each 90 cabinet unit is mounted almost entirely on the back thereof and may be removed with the back by the simple expedient of withdrawing the pivot pins which connect the locking means of adjoining back members, 95 and also the pins connecting with the door locking levers on the ends of intermediate divisions 15. The various members of each unit may be quickly and easily separated without the use of tools and, when so separated, may be easily handled or may be packed in small compass for shipment or storage and, when desired, may be easily and 100 quickly assembled.

Having thus described my invention, what I claim is:

1. In a knock-down cabinet, a base comprising a bottom board, members secured to the bottom board transversely thereof including a member at each end of the base 120 spaced a short distance inwardly from the end thereof and a pair of members intermediate said end members, the members of said pair being spaced a short distance apart, top boards resting upon said transverse members and each connecting an end member with the adjacent intermediate member, back and front skirtings resting upon the bottom board and secured thereto and to the ends of the transverse members; up- 125

right members disposed outside the end transverse members and between the members of the transverse pair; a top having transverse grooves at the ends and at a point intermediate the ends for the reception of the upright members and longitudinal grooves at front and back; a back resting upon the base and extending into the longitudinal groove of the top, and fastening means releasably connecting the members together.

2. In a cabinet, a sliding door support including a door guiding rib, a sliding door resting on said support, a member overlying the door presenting a channel in which the upper edge of the door is received, said channel being at its ends of such depth that the door is held against upward movement such as will disengage it from the bottom guide and said groove being deepened intermediate its ends for a distance equal to the width of the door to an extent permitting the door when partly open to be lifted from its bottom guide for removal.

3. In a cabinet, end and back members and a plurality of closure means including a till in combination with a common locking means for all of said members excepting the till, a lever pivoted intermediate its ends to an end of the cabinet adjacent the till, a roller on the end of said lever co-operating with a cam track provided therefor on the end of the till, a link connecting the opposite end of said lever with the closure locking means, and a plurality of aligned locking means for the till, the rearmost of said means being located for engagement by the till only after the same has been moved sufficiently to cause oscillation of the lever by the cam track for operation of the closure locking means.

4. In a cabinet including a plurality of sections and a plurality of closure means in

each section, a locking means in each section common to all the closure members thereof comprising upper and lower transverse levers pivoted intermediate their ends, upright links connecting corresponding ends of the levers, closure member locking bolts operatively connected to said links, in each pair of adjoining sections a transverse lever extending from one section into the next and pivoted intermediate its ends, and links pivotally connected between the ends of said lever and the uppermost of the transverse section levers whereby movement of the locking means in each section is transmitted to the next section, and actuating means connected to the locking system of one of the sections.

5. In a cabinet including laterally sliding closure members in one part and rearwardly sliding closure members in another part, a common locking means for the closure members of said cabinet comprising upper and lower transverse levers pivoted intermediate their ends to the cabinet back, upright links pivotally connected between the ends of said levers, locking bolts for the rearwardly slidable closure members carried by said links, locking bolts for the laterally slidable closure members being levers pivotally connected intermediate their ends to the cabinet ends, links connecting corresponding ends of said lever bolts with the transverse levers and spring latches on the closure members engageable with the bolts when in locking position and upon closing of the closure members, and means for operating the locking system to dispose the bolts in locking position.

In witness whereof, I have hereunto set my hand.

ROBERT C. WALSH.
